(57) **CLAIM**

The ornamental design for a package with surface ornamentation, as shown and described.

DESCRIPTION

FIG. 1 is a front, right perspective view of a package with surface ornamentation showing our new design;

FIG. 2 is a front elevation view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken dash-dot lines of even length illustrate portions of the package with surface ornamentation that form no part of the claimed design. The broken dash-dot lines of uneven length in the drawings define the boundaries of the claim and the broken dash-dot lines themselves form no part of the claimed design. The broken dash-dot lines of uneven length in the drawings define the boundaries of the claim and the broken dash-dot lines themselves form no part of the claimed design.
